CLAIM

The ornamental design for a foldable dog potty as shown and described.

DESCRIPTION

FIG. 1 shows a front perspective view of a foldable dog potty showing my new design;

FIG. 2 shows a front plan view bottom of the foldable dog potty of FIG. 1;

FIG. 3 shows a rear plan view of the foldable dog potty of FIG. 1;

FIG. 4 shows a left side plan view of the foldable dog potty of FIG. 1;

FIG. 5 shows a right side plan view of the foldable dog potty of FIG. 1;

FIG. 6 shows a top plan view of the foldable dog potty of FIG. 1;

FIG. 7 shows a bottom plan view of the foldable dog potty of FIG. 1;

FIG. 8 shows a perspective view of the foldable dog potty of FIG. 1 in an open state in use by a dog; and,

FIG. 9 shows a perspective view of the foldable dog potty of FIG. 1 in a closed state, sliding into a shipping box.

The broken lines shown in the drawings show environment of a dog and shipping box and form no part of the claimed design.
